(57) **CLAIM**

The ornamental design for a fabric, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top plan view of a fabric, showing my new design; and,

FIG. 2 is a top plan view of a second embodiment of the fabric.

In FIG. 1, the shading gradations represent color contrast. The colors shown in FIG. 2 are preferred colors which form an integral part of the second embodiment of the design.
